UNITED STATES PATENT OFFICE.

JAMES ROYS MILLER, OF OKMULGEE, OKLAHOMA.

PROCESS AND APPARATUS FOR REFINING OILS.

1,312,265.

Specification of Letters Patent. Patented Aug. 5, 1919.

Application filed March 13, 1918. Serial No. 222,176.

To all whom it may concern:

Be it known that I, JAMES R. MILLER, a citizen of the United States, residing at Okmulgee, in the county of Okmulgee and State of Oklahoma, have invented certain new and useful Improvements in Processes and Apparatus for Refining Oils, of which the following is a specification.

My invention relates to improvements in processes and apparatus for refining oil, and it consists in the steps hereinafter specified and in the means for carrying out the steps.

An object of my invention is to provide a process for cracking hydrocarbon for gasolene, toluol or benzene, which is more economical than the ordinary process, and which therefore produces these products at a relatively low cost.

A further object of my invention is to provide a process by means of which it is possible to produce synthesized products of desired composition at a relatively small cost.

A further object of my invention is to provide a novel form of apparatus for carrying out the cracking process, by means of which the process may be rendered continuous.

A further object of my invention is to provide a novel form of synthesis tower having a relatively large capacity thereby permitting the gases and vapors to be held therein a sufficient time to bring about the desired reaction, while not interfering with the continued operation of the device.

Other objects and advantages will appear in the following specification and the novel features of the invention will be particularly pointed out in the appended claims.

My invention is illustrated in the accompanying drawing forming part of this application, in which:

Figure 1 is a sectional view of a novel form of cracking tube, and synthesis tower, and

Fig. 2 is a view showing sections of a gas vapor receiver, a fractionator and a condenser.

In carrying out my invention, I provide a cracking tube 1 which is disposed in a vertical position as shown in Fig. 1, in the interior of a furnace 2, such as a gas fire apparatus which in the present instance is provided with injectors or burners 3, by means

of which liquid or gaseous fuel may be fed into the furnace. The arrangement is such that the hottest part of the tube is toward the bottom, and to this end an exit flue 4 is provided toward the bottom of the furnace so as to cause the products of combustion from the upper burner to pass downwardly. Communicating with the exit flue is a stack or discharge pipe 5 which is controlled by a damper 6. A pipe 7 also 65 communicates with the flue 4 and is provided with a damper 8.

At the bottom of the cracking tube 1 is a receiver 9 for the carbon and heavy oils. This is provided with a drain pipe 10 controlled by a valve 11. A pipe 12 leads from the receiver to the gas synthesis tower 14, the pipe 12 being controlled by a valve 13. The pipe 7 conducts the products of combustion into the space 15 which surrounds the synthesis tower. While I have shown the casing or body portion of the furnace 16 which heats the synthesis tower as being separate from the furnace 2, it will be obvious that these two structures might 80 be made integral without departing from the spirit of the invention.

The gas synthesis tower is preferably made of some conducting material such as sheet steel or other suitable heat conducting metal. It will be noted that the exit flue 17 is near the top of the heating device. Disposed within the synthesis tower is a central partition 18 which extends from the bottom of the device upwardly, but terminates short of a perforated plate or screen 19. At the bottom of the synthesis tower are two pipes 20 and 21 which are controlled by the valves 20^x and 21^x, respectively. A series of pipes 22, 23, 24, 25 and 26 which are controlled by the valves 22^x, 23^x, 24^x, 25^x and 26^x respectively, communicate with the gas synthesis tower at different points, the pipe 22 being disposed at a point below the upper end of the partition 18, while the pipes 23, 24, 25 and 26 are arranged below the pipe 22 as clearly shown in the drawing.

The pipes 22 to 26 inclusive communicate with the interior of the gas and vapor receiver 27, these pipes all having a downward bend as shown in the drawing. At the bottom of the receiver 27 is the pipe 28 which leads into the fractionator 29. The pipe 28 is provided with a pressure in- 110

dicator 30 and with a thermometer or temperature indicator 31. It is also provided with a pressure relief valve 32.

Disposed within the fractionator is a steam coil 33, steam being admitted into this coil through a pipe 34 connected with any suitable source, the pipe 34 being controlled by a valve 34^x. The upper end of the steam coil passes out of the casing of the fractionator and rearwardly into the top of the gas receiver 27, a valve 33^x being provided as shown in the drawing. At the top of the fractionator is a pipe 35 which leads to the condenser coil of the condenser 37. The latter is preferably filled with cold water so that the coil 36 is submerged.

From the foregoing description of the various parts of the apparatus, the process of refining the oil may be readily understood.

20 The process of producing gasoline is as follows:

The crude oil is admitted into the top of the cracking tube 1 through a pipe 38. The oil passes down the tube and due to the heating action is cracked into gases and vapors. These gases and vapors pass down through the tube into the carbon and heavy oil receiver 9 and thence through the vapor line 12 to the gas synthesis tower. The valve 30 13 is normally open, but may be closed when the contents of the receiver 9 is discharged through the pipe 10 so as not to disturb the gases and vapors in the synthesis tower. The cracking tube is maintained at a temperature greater than 500° F. and under a pressure of over 50 pounds.

The synthesis tower is maintained at the same pressure as that in the cracking tube but at a lower temperature. The gases and vapors from the vapor line pass into compartment A of the synthesis tower and thence over the partition 18. The light fixed gases pass through the perforated plate 19 into the upper portion of the tower and are 45 then pumped back again through the pipe 40 by means of the pump 39 into the cracking tube.

The heavier gases and vapors pass over into compartment B. Any vapors which 50 pass into the extreme top 45 of the synthesis tower are condensed and are returned to the tower. The trapped gases unite with the olefin hydrocarbons coming from the cracking zone, and form paraffin hydrocarbon 55 or other low boiling hydrocarbon, thus preventing the formation of higher polymerids and condensation products of the olefins. It will be noted that the tower has a relatively large capacity. This makes it possible to remove only a small per cent. of the gases and vapors that have been formed, which is not possible with most tube processes. It also permits the formation of synthesized products of desired composition.

65 By returning the fixed dry gases to the

cracking tube loss is prevented in fixed gases and the oil subsequently cracked does not form these gases when they are returned. The heavy oils that are brought into the tower pass down into the bottom of the compartment A.

The heavy or wet gases and vapors which pass into compartment B as before explained, now pass on out through the pipes 22 to 26 inclusive into the gas receiver. It 75 will be understood that not all of these pipes 22 to 26 are used at once but they are provided in order that the gases and vapors may be taken off at a lower or higher point as desired. Since the passage of the gases 80 and vapors through the synthesis tower is so slow, the heavy oils that have been carried over drop out to the bottom of the compartment B and are removed through the pipes provided for that purpose, thereby removing the oils from the gases and vapors. The gases and vapors conveyed through the pipes 22 to 26 inclusive now enter the receiver 27. This receiver is under substantially the same pressure as that on the synthesis tower, the pressure being derived from the steam coils 34 and 33 which convey dry steam through the fractionator and thence into the receiver. The purpose of providing the back pressure on the receiver 95 is to prevent the gases and vapors from passing too rapidly through the synthesis tower.

The back pressure is relieved by the release cock 33^x and then the gases and vapors 100 are permitted to pass into the fractionator through the pipe 28. The fractionator is maintained at substantially a temperature of 210-450 degrees F., by means of the steam coil 33, so that those heavy oils such as kerosene or gas oil, etc., may be removed. For this purpose, I provide a goose-neck trap, at the bottom of the fractionator, this trap being shown at 42.

The gases and vapors now pass out 110 through the fractionator at the top thereof, through the pipe 35 and thence to the condensing coil 36. In order to assist in this operation, steam may be admitted through the pipe 43 into the interior of the fractionator. The gravity of the condensed vapors 115 may be controlled to some extent by the fractionator.

The fixed or uncondensable gases which are carried through the condenser 36, may 120 be separated from the condensed vapors in any suitable manner and may be used for fuel or for any other purpose.

The process described above may be used for cracking the heavy hydrocarbons having 125 boiling points from 350° F. to 800° F. obtained from the distillation of crude petroleum, residuum or other hydrocarbon oils, to obtain low boiling products such as gasoline, cracked gasoline, synthetic gasoline or 130

gasolene substitutes. It may also be used in cracking solvent naphtha or other suitable hydrocabron for toluol, benzene, etc. The finished products will be low in unsaturated hydrocarbons which give bad color and odor to cracked gasolene made by other processes.

I claim:—

1. In an apparatus for refining oil, a cracking tube, a synthesis tower communicating with said cracking tube, means for returning light fixed gases from said synthesis tower to said cracking tube, a gas and vapor receiver in communication with said synthesis tower for receiving gases and vapors, a fractionator for removing heavier portions of said vapors and a condenser for condensing the lighter portions separated by the fractionator.
2. In an oil refining apparatus the combination of a cracking tube, a synthesis tower in communication with said cracking tube and said synthesis tower said cracking tube and said synthesis tower being under pressure, means for returning the lighter fixed gases from said synthesis tower to said cracking tube, means for drawing off the heavier oils carried over from said cracking tube, a gas and vapor receiver, means for introducing gases and vapors from said synthesis tower in said receiver, a fractionator in communication with said receiver, means for separating the heavier portions of the vapor in said fractionator, and a condenser for condensing the lighter portions thereof, said condenser being connected with the upper end of said fractionator.
3. In a device for refining oil, a vertically disposed cracking tube, a synthesis tower communicating therewith, a gas and vapor receiver communicating with the synthesis tower, a fractionator communicating with said gas receiver, a condenser communicating with the fractionator, means for heating the cracking tube and the synthesis tower, said cracking tube and synthesis tower being under pressure, means for returning a portion of the lighter gases from said synthesis tower to said cracking tube, means for drawing off the heavier oils carried over from said cracking tube to said synthesis tower, means for conducting gases and vapors from said synthesis tower into said gas receiver, means for heating said fractionator, and means for cooling said condenser.
4. In a device for refining oil, a vertically disposed cracking tube, a synthesis tower communicating therewith, a gas and vapor receiver communicating with the synthesis tower, a fractionator communicating with said gas receiver, a condenser communicating with the fractionator, means for heating the cracking tube and the synthesis tower, the cracking tube and the synthesis tower being under pressure, means for returning a portion of the lighter gases from said synthesis tower to said cracking tube, means for drawing off the heavier oils carried over from said cracking tube to said synthesis tower, means for conducting gases and vapors from said synthesis tower into said gas receiver, means for heating said fractionator, and means for cooling said condenser.
5. In a device for refining oil, a synthesis tower comprising a casing, means for heating the casing, means for introducing gases into the casing, means for withdrawing the heavier oils carried by the gases thus introduced, means for withdrawing the lighter fixed gases from the tower, and means for withdrawing vapors and gases of a specific gravity between the other products withdrawn from the synthesis tower.
6. In a device for refining oil, a synthesis tower comprising a casing, means for heating the casing, a pipe for introducing gas into the casing, a partition disposed within the casing for trapping gases and vapors, means for withdrawing light fixed gases from the top of the tower, and means for withdrawing heavier products on both sides of said partition.
7. In a device for refining oil, a synthesis tower comprising a casing, means for heating the casing, a pipe for introducing gas into the casing, a partition disposed within the casing for trapping gases and vapors, means for withdrawing light fixed gases from the top of the tower, means for withdrawing heavier products on both sides of said partition, and a perforated plate disposed between the upper end of the partition and the top of the casing.
8. The herein described process of refining oil which consists in cracking the oil, removing a portion of the gas and vapor thus formed, separating the gas thus removed into light fixed gases, heavy oils and vapors of a specific gravity between the light and the heavy products, fractionating the vapors, and condensing the lighter portions of the vapors thus fractionated.
9. The herein described process of refining oil which consists in cracking oil together with a portion of light fixed gas previously removed from a portion of the oil, separating the cracked gas and vapor into a light fixed gas, a heavier vapor and a still heavier oil, withdrawing the wet gas from the other products, fractionating the vapor into a heavy and a light product, separating out the heavy product, and condensing the light product.

JAMES ROYS MILLER.
